United States Patent

Des. 236,511
Patented Aug. 26, 1975

236,511

WATERING TROUGH

Richard E. Bunger, 5202 E. Washington St.,
Phoenix, Ariz. 85034

Filed Apr. 16, 1973, Ser. No. 351,282

Term of patent 14 years

Int. Cl. D30—03

U.S. Cl. D30—13

FIG. 3

FIG. 1 is a perspective view of a watering trough showing my new design;

FIG. 2 is a bottom perspective view thereof; and

FIG. 3 is a cross-sectional view taken along lines 3—3 of FIG. 1 with the cover portion shown in exploded relationship.

The section of the article omitted in FIG. 3 is substantially a mirror image of that shown.

I claim:

The ornamental design for a watering trough, as shown and described.
